(57) **CLAIM**

The ornamental design for a log splitting device, as shown and described.

DESCRIPTION

FIG. 1 is a front perspective view of a log splitting device showing the claimed design;

FIG. 2 is a left elevation view thereof;

FIG. 3 is a front elevation view thereof;

FIG. 4 is a right elevation view thereof;

FIG. 5 is a top plan view thereof;

FIG. 6 is a rear elevation view thereof; and,

FIG. 7 is a bottom plan view thereof.

The broken lines show environment, are for illustrative purposes only, and form no part of the claimed design.
